US0D1081715S

(12) **United States Design Patent** (10) Patent No.: **US D1,081,715 S**
(45) Date of Patent: ** Jul. 1, 2025

(54) **DISPLAY PANEL WITH GRAPHICAL USER INTERFACE**

(71) Applicant: **LG ELECTRONICS INC.**, Seoul (KR)

(72) Inventor: **Kyoungjune Shin**, Seoul (KR)

(73) Assignee: **LG ELECTRONICS INC.**, Seoul (KR)

(**) Term: **15 Years**

(21) Appl. No.: **29/945,775**

(22) Filed: **Jun. 5, 2024**

(30) **Foreign Application Priority Data**

Dec. 14, 2023 (KR) 30-2023-0051211

(51) **LOC (15) Cl.** **14-04**

(52) **U.S. Cl.**

USPC **D14/495**; D14/492

(58) **Field of Classification Search**

USPC D14/485-495

CPC G06F 3/0481; G06F 3/04817

See application file for complete search history.

(57) **CLAIM**

The ornamental design for a display panel with graphical user interface as shown and described.

DESCRIPTION

The FIGURE is a front view of a display panel with graphical user interface showing my new design.

The outermost broken lines illustrate a display panel and form no part of the claimed design. The remaining broken lines illustrate portions of the graphical user interface that form no part of the claimed design.

1 Claim, 1 Drawing Sheet
